UNITED STATES PATENT OFFICE.

JEREMIAH F. STAUFFER, OF PHILADELPHIA, PENNSYLVANIA.

DESIGN FOR A BICYCLE HANDLE-BAR.

SPECIFICATION forming part of Design No. 27,225, dated June 15, 1897.

Application filed February 10, 1897. Serial No. 622,862. Term of patent 7 years.

To all whom it may concern:

Be it known that I, JEREMIAH F. STAUFFER, a citizen of the United States, residing at Philadelphia, in the county of Philadelphia and State of Pennsylvania, have invented and produced a new and original Design for Bicycle Handle-Bars, of which the following is a specification, reference being had to the accompanying drawing, showing the same.

10 The drawing illustrates a perspective view of a handle-bar showing my design.

The leading features of my design consist in a spiral or convolute form in each of the handle-bars before they terminate in the

15 grips, as clearly shown in the drawing.

A represents the handle-bar post, which supports the handle-bars proper. These handle-bars first extend horizontally, as indicated at B, and upon either side of the post are so bent

20 as to form a spiral or convolute outline, as indicated at C, and finally terminate at approximately right angles to the horizontal sec-

tion B for the reception of the grips D. The effect of this curving of the handle-bars is to present in an exaggerated form what is known 25 as "ram's horns."

When handle-bars made in accordance with my design are viewed from whatever standpoint possible, they present a combination of curves, gyrations, or convolutions which are 30 at once pleasing to the eye and give to the bars a more substantial and massive look than would otherwise be the case.

What I claim is—

The design for a bicycle handle-bar, as herein shown and described.

In testimony whereof I have hereunto affixed my signature in the presence of two subscribing witnesses.

JEREMIAH F. STAUFFER.
